(57) CLAIM

The ornamental design for a grille for vehicle, as shown and described.

DESCRIPTION

FIG. 1 is a perspective view of a grille for vehicle showing our new design.

FIG. 2 is a front view thereof.

FIG. 3 is a right side view thereof.

FIG. 4 is a left side view thereof.

FIG. 5 is a top view thereof.

FIG. 6 is a perspective view of another embodiment of the grille for vehicle.

FIG. 7 is a front view thereof.

FIG. 8 is a right side view thereof.

FIG. 9 is a left side view thereof; and,

FIG. 10 is a top view thereof.

The de-emphasized portions shown in the drawings illustrate environmental structure for a grille for vehicle that form no part of the claimed design.
